FOREIGN PATENT DOCUMENTS

EP 2564481 B1 9/2015

Primary Examiner — Derrick E Holland*Assistant Examiner* — Jennifer O King(74) *Attorney, Agent, or Firm* — Christopher S. Clancy;
James H. Williams; Aimee E. McVady(57) **CLAIM**

The ornamental design for a vertical cable manager, as shown and described.

DESCRIPTION

FIG. 1 is a front left side perspective view of a vertical cable manager;

FIG. 2 is a front view thereof;

FIG. 3 is a side view thereof;

FIG. 4 is a rear view thereof;

FIG. 5 is a another side view thereof; and,

FIG. 6 is a top view thereof.

The broken lines shown represent portions of the vertical cable manager that form no part of the claimed design.

1 Claim, 6 Drawing Sheets(56)
